UNITED STATES PATENT OFFICE.

PETER SANTURELLO, OF COLUMBUS, OHIO.

HAIR-CURLING APPARATUS.

Application filed July 29, 1927. Serial No. 209,378.

This invention relates to hair curling apparatus and is particularly directed to the provision of means for winding and curling hair upon a mandrel as a preliminary step in the process of dressing hair to produce what is known as a permanent wave effect, and an outstanding object of the invention is to provide means whereby the curling operation may be rapidly accomplished in a satisfactory and uniform manner without injury to the patron, damaging the hair or requiring the services of a highly trained operator.

Another object of the invention is the provision of a positive, effective and easily manipulated gripping and locking device provided in connection with the mandrel for quickly and securely attaching the latter to a lock of hair adjacent the scalp.

Another object of the invention is to so construct the device that when the hair is being wrapped spirally and tightly around the mandrel the operation will be carried out without pulling the hair of the patron so as to cause physical discomfort.

Another object of the invention is the provision of a device for mechanically winding hair about a mandrel in a taut helically applied manner to produce uniform, lasting and equally tensioned curls and wherein all parts of the hair thus wrapped around the mandrel will be under substantially equal tensional strains.

A further object of the invention resides in the provision of a holder for the reception of the curl producing devices, said holder being in the nature of a magazine permitting of the accommodation of a number of the curl devices for the purpose of expediting the successive wrapping operations.

Other important features of the invention will appear as the description progresses and will be more particularly defined in the appended claims. The various objects may be obtained by the embodiment illustrated in the accompanying drawings, wherein similar reference characters designate similar parts and wherein:

Figure 1 is a perspective view of a hair

curling mandrel and wrapping device 50 formed in accordance with the present invention,

Figure 2 is a similar view showing the magazine holder in a slightly different position from that disclosed in Figure 1, 55

Figure 3 is a perspective view of the mandrel and the curling sleeve,

Figure 4 is a vertical sectional view taken through the magazine holder showing a plurality of the curling sleeve arranged 60 therein,

Figure 5 is a view in front elevation of the holder and an associated curling sleeve,

Figure 6 is a detail perspective view of one end of the holder showing the spiral recess formation in one end thereof, 65

Figure 7 is a perspective view of a curling sleeve,

Figure 8 is a detail perspective view of the extension element used in connection 70 with said sleeve,

Figure 9 is a similar view of the sleeve with the extension element applied thereto,

Figure 10 is an end elevation of said sleeve, 75

Figure 11 is a detail cross-sectional view taken through the locking head of the mandrel, showing said head in an open or releasing position,

Figure 12 is a similar view showing the 80 head in a closed or locking position,

Figure 13 is a vertical longitudinal sectional view taken through the locking head.

Referring more particularly to the drawings there has been shown a mandrel 1, 85 which is preferably of hollow cylindrical construction, but which obviously may have any desired cross-sectional shape and dimensions of any convenient magnitude. Attached to one end of the mandrel 1 is a 90 gripping and locking device or head for securing the mandrel to a lock of hair in close proximity to the scalp.

This gripping device consists of a metallic casing formed to comprise spaced disk like 95 plates 2—2, united by a peripheral wall 3. The plates 2—2 and the walls 3 are provided with a radial slot 4 formed to include curved

side walls, as shown more particularly in Figures 11 and 12. The mandrel 1 is rotatably mounted in connection with the plates 2 and in this instance is provided with a spiral locking spring or member 5, and the construction is such that upon effecting relative rotation on the part of the mandrel and the locking device the spring may be rotated from the position disclosed in Figure 11 to that disclosed in Figure 12. When the parts are positioned as in Figure 11 a tuft or lock of hair may be positioned in the open slot without interference on the part of the spring. However, upon rotating the locking head in the mandrel relatively the spring will be moved to assume the closed or clamping position indicated in Figure 12, wherein it will be observed that the inner convolution of the spring will be brought adjacent to the mandrel so as to frictionally grip and clamp the hair in a securely confined manner between said spring and said mandrel, thus providing a secure anchorage, as it were, between the hair and the mandrel, which relieves strain on the scalp and permits the hair to be tightly and tautly wrapped in helical convolutions longitudinally around the mandrel without discomfort to the patron. The outer end of the locking head may be provided with a pad as at 6 so as to prevent the metallic part of the device contacting with the scalp and to avoid any discomfort to the patron when the device is subsequently heated to set the curl or wave.

To tightly curl or wrap the hair around the mandrel use is made of a primary winder 7 and a handle or secondary winder 8. The handle is formed to include an elongated tubular cylindrical body of sheet metal or the like of suitable diameter so that it may be readily gripped by the hand and rotated axially about the axis of the mandrel. The winder is of sufficient length to receive a plurality of the primary winders 7, as shown in Figure 4, and in this manner the handle serves as a magazine permitting of the retention therein of a suitable number of the primary winders which are so arranged that the same may be used successively upon different mandrels, thus providing a convenient means for retaining the rather small primary winders preventing the same from becoming lost or misplaced and at the same time providing for a more systematic and rapid operation.

Each of the primary winders comprises a tubular metallic body having the forward end thereof formed to include a longitudinally extending shoulder 9 and a substantially spiral face 10 and internally the winder is formed to include at its forward end a relatively enlarged chamber 11 which terminates in a transverse helical face 12. The forward part of the winder 7 is formed to

include a longitudinally extending rib 13, which is receivable within a longitudinally extending slot 14 formed in the tubular holder 8. To the rear of the rib 13 each of the winders terminate in a split clamping body 15, which is adapted to frictionally engage with the walls of the mandrel 1 so as to resist sliding movement thereon.

The tubular holder at its forward end is formed to include a helical slot 16 into which the tuft or hair is initially received, and upon rotating the holder it will be seen that the hair tuft will be forced toward the inner or rear part of the slot 16 and thence to engagement with the spiral face 10 and shoulder 9 of the winder 7. By this construction when the holder is rotated the winder is rotated in unison therewith and the hair is wrapped helically in tight successive layers, uniformly tensioned, around the mandrel, the winder and holder being moved longitudinally outwardly as the hair is wound around the mandrel, this being accomplished by the engagement of the hair with the helical face 12 of the winder 7.

Rearward movement of the winder in the forward part of the holder is prevented by the provision of a leaf spring 17, which is carried by the holder and projects through a slot 18 formed therein so that the free end of the spring will engage normally with an annular shoulder 19 provided upon the exterior surface of the winder. At the open end of the holder there is a spring 20 which includes an inturned portion 21 so disposed as to prevent the winders arranged within the holder from dropping out when the holder is manipulated. It will be understood that the ribs 13 of the winders project through the longitudinal slot 14 and may be engaged by the thumb of the operator so as to be advanced successively into an operating position within the front end of the holder. Additional ribs 22 may be formed exteriorly of the holder to facilitate the grip of the operator when the device is being rotated. A furrow 23 is formed on the rear end of the holder to strengthen the latter and to overcome the weakness therein provided by the slot 14.

After the hair has been thus wrapped on the mandrel the holder is removed together with the inactive primary winders, if any of such winders are left within the holder, and the free end of the hair is held clamped by the active winder remaining on the mandrel, which grip the free ends of the hair and prevent their accidental removal thereof or unwrapping from their tautly wound position on the mandrel. The wrapped hair is then covered with a liquid saturated cloth body and the mandrel is inserted in a heating unit, preferably of the electric resistance type shown in my copending application Serial Number 209,379 filing date 130

July 29, 1927 in order to steam or heat treat the hair for a requisite period of time to insure the desired set of the curl.

From the foregoing description it will be apparent that I have produced a device which may be employed for curling hair in a minimum time period and in a uniform and systematic manner. The invention in addition to greatly reducing the time also does more satisfactory work, requires less skill than other processes, curls the ends of the hair, subjects all parts of the hair to substantially the same strain, eliminates strings and the inconvenience and damage attending their use and secures other desirable results apparent to those skilled in the art.

What is claimed is:

1. In a hair waving apparatus, the combination of a mandrel, a recessed casing rotatably mounted on one end of said mandrel for attaching the latter to a lock of hair in close proximity to the root ends thereof, and a helical device secured to said mandrel and positioned within said casing to frictionally engage and clamp in locked relationship therewith the lock of hair extending through the recessed portion of said casing.
2. A hair waving device of the class described comprising a mandrel, means for attaching said mandrel to a lock of hair in close proximity to the root ends thereof comprising a casing arranged on one end of said mandrel and rotatable relatively thereto, and a helical device carried by said mandrel and movable across the recesses provided in said casing to frictionally grip the hair between said device and said mandrel without twisting the hair.
3. In a hair waving apparatus, the combination of a mandrel, means for positioning one end of said mandrel adjacent to the root end of a lock of hair on the scalp embodying a head rotatably mounted on one end of said mandrel and having a hair receiving recess formed therein, and means movable in unison with said mandrel to lock the hair within said recess by a direct inward radial movement without placing the hair under tension through rotation or twisting thereof.
4. In a hair waving device, a mandrel, a head arranged at one end of said mandrel and provided with a radial recess for the reception of a lock of hair, and helical clamping means rotatable within said head for drawing the hair into the inner part of said recess and clamping the same to said mandrel.
5. In hair waving apparatus, a mandrel, a head arranged upon one end of said mandrel and provided with a radial recess for the reception of a lock of hair, and a helical clamping member movable across the recess

in said head to frictionally engage and clamp the hair disposed therein, said helical member functioning to force the hair into the inner part of said recess and to thereby clamp the hair without placing the same under tensile stress by twisting or pulling the same.

6. In hair curling apparatus, a mandrel, a head revoluble upon one end of said mandrel, said head being provided with a radial recess, and a helical clamping spring carried by said mandrel and arranged within said head, said spring upon relative rotation of said head and mandrel being movable across the recess of said head to clamp the hair extending therethrough in locked engagement with said mandrel.

7. In a hair waving apparatus, the combination of a mandrel, of a winder for curling strands of hair around said mandrel, and a magazine holder for rotating said winder and formed to permit of its withdrawal from said winder after a curling operation.

8. In a hair curling apparatus, the combination of a mandrel embodying means for positioning one end thereof in close proximity to the root ends of a lock of hair on the scalp, of a winder for curling said lock of hair around said mandrel, and an enlarged holder for receiving said winder and facilitating its rotation.

9. In a hair curling apparatus, the combination of a member about which a strand of hair is to be wound, a device for winding said strand of hair spirally around said member, and a magazine holder for said device, said holder being of such form as to facilitate the rotation of said device and to permit of the accommodation therein of a plurality of said devices.

10. In hair waving apparatus, a mandrel, a winder rotatably and slidably mounted upon said mandrel and a holder for receiving said winder and rotating the same, said holder and winder being provided with complementary hair guiding and wrapping surfaces.

11. In a hair waving apparatus, the combination of a mandrel, means provided at one end of said mandrel for locking a hair bunch thereto, a winder rotatably and slidably mounted upon said winder, a holder for the reception of said mandrel complementary and helical hair guiding and receiving surfaces provided in connection with said winder and holder for helically applying the hair around said mandrel, and interlocking connections between said winder and said holder admitting of unitary rotation thereof.

12. In hair waving apparatus, a mandrel, a winder rotatably and slidably mounted upon said mandrel and a holder for receiving said winder and rotating the same, said holder and winder being provided with

complemental hair guiding and wrapping surfaces, and means formed upon said holder and winder for holding said surfaces of the winder and the holder in operation 5 aligned with each other.

13. In a hair waving apparatus, the combination of a mandrel, means provided at one end of said mandrel for locking a bunch of hair thereto, a winder rotatably and slidably mounted upon said mandrel, a maga-

zine holder for said winder formed with an open ended longitudinal slot in its side wall, said holder being of a length so as to accommodate therein a plurality of said winders, and a longitudinal rib provided upon each 15 of said winders and arranged to be received within the slot of said holder.

In testimony whereof I affix my signature.

PETER SANTURELLO.
